UNITED STATES PATENT OFFICE.

JULIUS SCHWANTES, OF MILWAUKEE, WISCONSIN, ASSIGNOR TO THE PALMOLIVE COMPANY, OF MILWAUKEE, WISCONSIN, A CORPORATION OF WISCONSIN.

SHAVING-SOAP CONTAINER.

Application filed January 20, 1919. Serial No. 272,120.

To all whom it may concern:

Be it known that I, JULIUS SCHWANTES, a citizen of the United States, and resident of Milwaukee, in the county of Milwaukee and State of Wisconsin, have invented new and useful Improvements in Shaving-Soap Containers, of which the following is a description, reference being had to the accompanying drawings, which are a part of this 10 specification.

This invention relates to improvements in soap containers for holding stick soap preferably used for shaving purposes.

It is one of the objects of the present invention to provide a soap container adapted to contain a stick of soap in position to be conveniently used when the cover of the container is removed, and to form substantially an air tight closure for the soap when the 20 cover is in closed position.

A further object of the invention is to provide a soap container having a cover portion threaded to a base or soap holder portion in a manner to permit the easy removal or replacement of the parts.

A further object of the invention is to provide a soap container having a base or holder portion so constructed as to be easily engaged by a stick of soap and which will 30 firmly hold the stick soap removably in position.

A further object of the invention is to provide a soap container having a two part base or holder portion in which said parts 35 are revolvably connected together and provided with a yielding expandible member controlled by the relative movement of the parts for clamping a stick of soap thereto.

A further object of the invention is to provide a soap container having means whereby when the soap has been used to a point close to the inner end of the holder portion the remaining piece may be released and conveniently pushed outwardly and re-clamped so that only a short end part of the soap is engaged by the holder portion to eliminate waste.

A further object of the invention is to provide a soap container which is of simple 50 construction, is strong and durable and is well adapted for the purpose described.

With the above and other objects in view the invention consists of the improved soap container and its parts and combinations as

set forth in the claims, and all equivalents 55 thereof.

In the accompanying drawing in which the same reference characters indicate the same parts in all of the views:

Fig. 1 is a vertical sectional view of the 60 improved soap container on an enlarged scale;

Fig. 2 is a transverse sectional view taken on line 2-2 of Fig. 1;

Fig. 3 is a vertical sectional view of the 65 base or holder portion of the container with the yielding expandible member shown in expanded position and a part of a stick of soap indicated by dotted lines;

Fig. 4 is a side view on a reduced scale of 70 the base portion thereof showing a stick of soap contained therein, and

Fig. 5 is a side view of the casing or cover.

Referring to the drawing the numeral 8 indicates the base portion, 9 the revoluble 75 controlling member, 10 the expandible member, 11 the casing or cover, and 12 a stick of shaving soap contained therein.

The base portion 8 is preferably of circular shape in cross section with a lower 80 rounded handle portion 13 and a plurality of embossed spirally trending side ribs 14 forming threads which are engaged by corresponding threads 15 formed in the lower end portion of the cover 11 to provide a 85 threaded connection therebetween. The threads of each member are preferably four in number so that the cover may be conveniently removed or replaced by a quarter turn of either member.

The cover is in the form of a tube with a closed upper end and is of a length and diameter to cover but not touch the stick of soap mounted in the base portion.

The upper edge portion of the base is bent 95 inwardly to form a holding flange 16 which extends over the annular outwardly extending lower flange 17 of the revoluble controlling member 9 and retains said revoluble member in position. The upper edge portion 18 of the revoluble member is flanged inwardly to closely fit the diameter of the stick of soap. The expandible member 10

consists of a strip of flat spring metal of slightly oval form in cross-section which is 105 bent spirally a plurality of convolutions of a diameter less than the diameter of the stick of soap adapted to be clamped there-

by. The upper end portion of the expandible member is bent outwardly slightly and is soldered or otherwise connected to the upper portion of the revoluble member 9 as indicated by the numeral 19. The lower end portion of the expandible member is likewise slightly bent outwardly and is soldered or otherwise connected to the base 9 as indicated by the numeral 20. As the convolutions of the expandible member are wound very close and when in contracted position rest upon each other the revoluble member is held in its uppermost position.

An opening 21 formed in the bottom portion 8 and loosely covered by a plate 22 provides for the insertion of a pencil or other means for forcing out the small unused remaining piece of soap. The lower portion of the stick soap may be covered with tin foil 23 to keep air therefrom if desired, and portions of the foil removed as the soap is used.

In use the revoluble member is turned a partial revolution to unwind the expandible member with the result that the bore of the expandible member will be increased in diameter to an extent greater than the diameter of the stick of soap so that the end of the stick of soap may be easily inserted into the bore of the expandible member. When inserted the revoluble member is released and the convolutions of the expandible member will automatically contract and firmly clamp the stick soap in position. When the stick of soap is almost used up the clamped piece may be pushed upwardly and re-clamped to expose the greater part of the remaining portion, by inserting a pencil through the bottom opening by which the expandible member is expanded and pushing upwardly. When the soap is reduced in size to an extent that it is too small to be clamped in position, a new stick of soap may be inserted in the expandible member and the remaining portion may be moistened and pressed on the upper end of the new stick and it will adhere thereto and thus avoid waste.

From the foregoing it will be seen that the invention is of very simple construction, and is well adapted for the purpose described.

What I claim as my invention is:

1. A soap container, comprising a base member, means when in normal position for clamping one end portion of a stick of material thereto and manually expandible by a revoluble movement only to release the stick of material, and a casing covering the stick of material and removably connected to the base member.

2. A soap container, comprising a base member, expandible means when in normal position for clamping one end portion of a stick of material thereto and manually expandible by a revoluble movement only to release the stick of material, and a casing covering the stick of material and removably connected to the base member. 65

3. A soap container, comprising a base member, a revoluble member connected thereto, a spiral member connected to the base member and to the revoluble member and expandible to increase its bore by a revoluble movement only of the revoluble member, and an enclosing casing removably connected to the base member. 70 75

4. A soap container, comprising a base member, an expandible spiral member carried thereby and having a bore, a revoluble means connected to the spiral member for increasing the diameter of the bore thereof when turned, and a casing removably connected to the base member. 80

5. A soap container, comprising a base member, a revoluble member carried thereby 85 and held against endwise movement, a coiled spring extending into the base member and having one end connected thereto and the other end connected to the revoluble member, and a casing removably connected to the 90 base member.

6. A soap container, comprising a base member, a revoluble member carried thereby and held against endwise movement, a strip of spring metal of slightly oval form in 95 cross section bent spirally to form a plurality of convolutions of less diameter than the stick of material it is adapted to hold, the lower end portion of said strip being connected to the base member and the upper end portion being connected to the revoluble member, and a casing removably connected to the base member. 100

7. A soap container, comprising a base member having a plurality of spirally trending ribs, a revoluble member journaled in the base member and having its upper edge portion flanged inwardly, a strip of spring metal bent spirally to form a plurality of convolutions of less diameter than the stick of material it is adapted to hold, the lower end portion of said strip being connected to the base member and the upper end portion being connected to the revoluble member, and a casing having a plurality of spirally trending grooves for engagement with the ribs of the base member for removably connecting the parts together. 105 110 115

In testimony whereof I affix my signature.
JULIUS SCHWANTES,
